J. Lyman
Boot Pattern.

N° 10,134.

Patented Oct. 18, 1853.

UNITED STATES PATENT OFFICE.

DANIEL LYNAHON, OF BUFFALO, NEW YORK.

CUTTING BOOTS.

Specification forming part of Letters Patent No. 10,134, dated October 18, 1853; Reissued May 9, 1854, No. 264.

To all whom it may concern:

Be it known that I, DANIEL LYNAHON, of the city of Buffalo, county of Erie, and State of New York, have invented a new and useful Improvement in the Mode of Making Uncrimped Boots, by which They are Cut to Set Better, Securing the Seams from Ripping and Giving a General Beauty; and I do hereby declare that the following

10 is a full and exact description of the said invention.

I first cut the vamp according to Figure 1 and fold it together as is done in all cases; secndly, I cut the piece, Fig. 2, and sew it 15 on the side C, of the vamp k—j; the opposite half of the same size being a substantial part of the vamp. I then sew up the center of the front which form the seams l—m and m—n. Then I add to these the 20 top o which joins them at p—n. Next I cover the seam m—n with the tongue i, (which is also a part of the vamp), by

stitching it at each side of the seams m—w, which prevents it from being seen, and from 25 ripping by means of the working of the foot in the boot. Then I bring the same tongue across the seam p—n, to the top, which keeps that seam also in its place and prevents it from ripping: thus making a permanent and neat setting front. The rest of the boot 30 is made after the ordinary mode.

What I claim as new in this mode is—

The tongue i, which first gives to the vamp a more exact crimped turn, secondly, covers 35 the seam m—n from being seen, and prevents it from ripping, and thirdly, keeps the seams l—m and p—n permanent by receiving the strain that comes on them when drawing on the boot.

DANIEL LYNAHON.
